ELECTRIC CONTROL FOR DOOR OPENING
AND CLOSING MECHANISMSBoley A. Andrews, Kansas City, Kans., assignor,
by mesne assignments, to The Vendo Company,
Kansas City, Mo., a corporation of Missouri

Application November 22, 1948, Serial No. 61,474

2 Claims. (Cl. 318—266)

1

This invention has to do generally with door actuating mechanism and more particularly to an electric circuit for automatically controlling the operation of such mechanism to move a door to and from a closed position through the mere expedient of causing the energization of an electric motor or like prime mover.

By way of explanation, there are today many different types of mechanical contrivances obtainable upon the open market capable of moving a closure such as a garage door, toward and from an open position, and in my co-pending application, filed on even date herewith and entitled "Motor Actuated Door Operator," a particular type of such door operating means is disclosed.

It is to be understood at the outset that the electric circuit forming the subject matter hereof, is not necessarily limited in its operation to use with door mechanism such as that set forth in my co-pending application, but may be used generally with door actuating structures having the minimum requirements to be hereinafter set forth. Accordingly, the mechanism that interconnects the electric motor hereinafter mentioned, with the door to be actuated, has not been illustrated. In the same manner, certain switches to be referred to during the course of the following specification, may be operated by the door itself in conventional manners and such switch operating means has also been eliminated from this disclosure.

It is the primary object of the present invention to provide an electric circuit for controlling the operation of door actuating mechanism having as a part thereof, a pair of relays for closing and opening the door respectively, said relays, together with other parts of the circuit, being so arranged that only one of the relays can be energized at one time.

Another important object of the present invention is the provision of electric control means for door opening and closing mechanisms having a pair of switch assemblies for deenergizing the electrical circuit when the door reaches the ends of its path of travel in the closed and open positions respectively, the circuit being so arranged that movement of only one of the door operated switches during the cycle of operation will have effect upon the circuit itself.

A further object of the present invention is to provide an electric circuit of the above mentioned character having timing means interposed therein and operable only when the door moves toward one end of its path of travel for automatically deenergizing the entire circuit after a predeter-

2

mined period of time if, for some reason, the door does not reach said end of its path of travel in the normal lapse of time.

Other objects of the present invention will be made clear as the following specification progresses, reference being had to the accompanying drawing, wherein the single figure is a schematic wiring diagram of an electric control for door opening and closing mechanisms made in accordance with the present invention.

In the circuit illustrated by the drawing, there is illustrated an armature 10 and a field coil 12 forming a part of a high speed, universal, reversible electric motor. This motor may be coupled with any suitable mechanism to a door to be actuated thereby for moving said door to an open position when the motor shaft rotates in one direction and moving the door to a closed position when the motor shaft rotates in the opposite direction.

As above mentioned, the particular type of mechanism that is utilized for interconnecting the motor with the door, is of no consequence to the present invention and since the same may embody any conventional structure well within the knowledge of those skilled in the art, the same has not been illustrated and will not be further described.

The electrical circuit of the drawing also includes a limit switch 14 that is disposed for movement toward and from a closed position by the aforesaid door opening and closing mechanism, coupled with the electric motor formed by armature 10 and field 12. While it is contemplated that the switch 14 be so arranged within the door actuating mechanism as to automatically open whenever an overload occurs in the door itself or the mechanical parts connected therewith, it is sufficient to note that for the purpose of the present invention, switch 14 may be coupled simply with the door itself for movement to the open position when the door reaches the closed position and for immediately opening when the door commences its movement toward the open position.

A second switch 16 operates in much the same manner so as to be disposed in the closed position when the door is closed and in the open position when the door is open.

By way of clarification, the switch 14 is open and the switch 16 is closed as illustrated in the drawing, whenever the door is closed. Conversely, when the door is in the open position, the switch 14 is closed and the switch 16 opens.

In addition to the electrical components of

the circuit thus far mentioned, there is provided a door opening relay, broadly designated by the numeral 18, a door closing relay broadly designated by the numeral 20, a switch 22, a thermal switch 24, a switch 26 ganged with the switch 16, a lamp 28 and a transformer 30.

Transformer 30 is provided with a primary winding 32 and a secondary coil 34. The relay 18 has a coil 36 and a plurality of switches 38, 40, 42 and 44. It is to be noted that the switches 38, 42 and 44 of relay 18 are normally open, whereas the switch 40 thereof is normally closed.

The relay 20 is identical with the relay 18 and includes a coil 46 and a number of switches 48, 50, 52 and 54. Here again, the switches 48, 52 and 54 are normally open, whereas the switch 50 of relay 20 is normally closed.

Thermal switch 24 has a heating element 56 and a contact arm 58. The switch 22 is illustrated as an ordinary push-button type of make and break mechanism that may well be conveniently disposed adjacent the garage doors. Obviously, it is within the scope of this invention that the switch 22 be operated by any one of the present day automatic garage door opening devices that includes an ultrasonic whistle and a radio receiver for receiving such sounds and causing the closing of switch 22.

A pair of lead lines 58 and 60 have connection with a source of alternating current electrical energy (not shown) for supplying the primary 32 of transformer 30 as well as other electrical components in the manner about to be described. Secondary 34 of transformer 30 receives energy from primary 32, the latter being connected with lead lines 58 and 60 by wires 62 and 64 respectively.

Assuming first that the door to be controlled by the circuit hereof, is in the closed position wherein the switch 16 is closed and the switch 14 is open as illustrated, the circuit for energizing the door opening relay 18 after closing of switch 22, is traceable as follows:

From secondary 34 through lines 66, 68 and 70, closed switch 22, lines 72, 74, 76 and 78, coil 36 of relay 18, line 80, normally closed switch 50 of relay 20, lines 82 and 84, closed switch 16 and wire 86 to secondary 34.

Energization of coil 36 of relay 18 will move the switches 38, 42 and 44 from the normally open position to a closed position, and also open the normally closed switch 40. Closing of the switch 38 operates to hold the relay 18 energized while the door moves from the closed position to the open position irrespective of re-opening of switch 22, through the following circuit:

From secondary 34 of transformer 30 through wires 66 and 88, closed switch 38 of relay 18, wires 90 and 78, coil 36 of relay 18, wire 80, closed switch 50 of relay 20, wires 82 and 84, closed switch 16 and wire 86 to secondary 34.

With the relay 18 thus held in the closed energized condition, the circuit for energizing the armature 10 and field 12 of the electric motor, to cause rotation of the drive shaft of such motor in one direction to open the door, is traced as follows:

From lead line 58 through wire 92, normally closed contact arm 58 of thermal switch 24, wires 94 and 130, closed switch 52, wires 132 and 102, armature 10, wires 100 and 134, closed switch 54, wires 136 and 110, field 12 and wires 112 and 114 to lead line 60.

As above explained, when the door moves to

the fully open position, the switch 16 is automatically opened. Since the circuit above traced through switch 38 for holding relay 18 closed, includes this switch 16, opening of the latter will obviously deenergize the coil 36 of relay 18 with a resultant re-opening of switches 42 and 44 that in turn deenergize the circuit through armature 10 and field 12.

The electric motor will thus discontinue its operation and the door will come to rest in the fully opened position until such time as the push-button 22 is again moved to a circuit closing position.

It is to be noted at this point that movement 15 of the switch 16 to the open position also moves the switch 26 to a position closing a circuit through the lamp 28, this circuit being traced as follows:

From primary 32 of transformer 30, through 20 lines 64, 114 and 116, lamp 28, wire 118, closed switch 26 and line 120 to secondary 34.

It is contemplated that the lamp 28 be positioned next adjacent the door to be controlled 25 by the present invention for lighting the garage and runway thereto while the door is in the open position.

Remembering that initial movement of the door from the fully closed position toward the open position, causes the switch 14 to move to 30 a closed position, the circuits for causing the door to return to a closed position upon initial closing of switch 22, are traced as follows:

From secondary 34 through wires 66, 68 and 70, closed switch 22, wire 72, coil 46 of relay 35 20, wire 122, normally closed switch 40 of relay 18, wire 124, closed switch 14 and wires 126 and 86 to secondary 34.

This just mentioned circuit through coil 46, will 40 cause the switch 50 of relay 20 to open and will close the switches 48, 52 and 54 of relay 20. Closing of the switch 48 will hold the coil 46 energized, irrespective of re-opening of switch 22 through the following circuit:

From secondary 34 of transformer 30, through 45 wires 66 and 68, closed switch 48, wires 128 and 74, coil 46, wire 122, normally closed switch 40 of relay 18, wire 124, closed switch 14 and wires 126 and 86 to secondary 34.

With the relay 20 thus held in the closed position, 50 the circuit through armature 10 and field 12 of the electric motor capable of rotating the drive shaft thereof in a reversed direction for returning the door to the closed position, is traced as follows:

From lead 58 through wire 92, normally closed contact arm 58 of thermal switch 24, wires 94 and 130, closed switch 52, wires 132 and 102, armature 10, wires 100 and 134, closed switch 54, wires 136 and 110, field 12 and wires 112 and 114 to lead 60.

As the door moves from the open position toward the closed position, the switch 16 is re-opened and when the door reaches the fully closed position, the switch 14 will re-open. Since switch 65 14 is within the circuit through switch 48 for holding coil 46 energized, opening of such switch 14 will obviously deenergize relay 20 and stop the motor that includes armature 10 and field 12. De-energization of the motor is occasioned by re-opening of switches 52 and 54 of relay 20.

It is also apparent at this point that if the switch 14 is operably associated with mechanism capable of moving the switch 14 to an open position, whenever an overload occurs with respect to 70 the door movement, the circuit will be automat-

ically deenergized through such opening of switch 14, stopping further movement of the door toward the closed position.

The thermal switch 24 is of conventional character and is provided within the circuit as a safety feature for automatically deenergizing the motor circuit, if for some reason the motor stalls during the door opening operation. Switch 24 is so timed as to deenergize the motor circuit after an expiration of time, preferably equal to twice the normal door opening time. The heating element 56 is so arranged as to be energized only while the door is moving toward the open position and such operation is accomplished by interposing the element 56 within a circuit that includes the switch 50 of relay 20. Thus, when the normally closed switch 50 of relay 20 is opened through energization of the relay 20 to move the door to the closed position, element 56 will not heat. However, when switch 22 is closed to operate relay 18, the element 56 is energized through the following circuit:

From secondary 34 of transformer 30, through switch 16 (that is in the closed position while the door moves toward the open position), wires 84 and 82, closed switch 50, wires 80 and 138, element 56, wires 140, 78 and 90, switch 38 (closed by virtue of energization of coil 36), and wires 86 and 66 to secondary 34. When the element 56 reaches a sufficiently heated condition, contact arm 58 will be caused to open and thereby deenergize the circuit through the electric motor that operates to cause the door to move to the open position.

It is apparent from the foregoing that closing of switch 22, whenever the switch 14 is open and the switch 16 is closed, will always cause the door to move from the open position to the closed position. Conversely, closing of the switch 22 whenever the switch 14 is closed and the switch 16 open, will cause the door to move from the closed position to the open position.

It is also clear that when the door closes to thereby open switch 14, such door will not immediately move toward the open position until switch 22 is again closed because of the fact that closing of switch 16 cannot cause energization of the motor circuit in the absence of closing of switch 22. In the same way, closing of switch 14 as the door commences its opening movement, cannot close the circuit as long as the switch 22 is open.

With the relays 18 and 20 interconnected in the manner just above set forth, a further safety feature is provided preventing any operational effects if the operator should hold the switch 22 in the closed position while the door moves through its cycle. For instance, closing of switch 22 for energizing relay 18, automatically opens the switch 40 of relay 18 and as soon as this action takes place, there is no open circuit through coil 46 and switch 22 even though the latter is held closed because of the fact that switch 40 of relay 18 is open. Conversely, closing of the switch 22 to energize coil 46 will automatically open the switch 50 and when this last mentioned switch opens, a holding of the switch 22 in a closed position will not energize the coil 36 because of the fact that the circuit for coil 36 includes the open switch 50.

Manifestly, all of the safety precautions that are necessary in door operating mechanisms have been provided in the electric circuit above described and forming the subject matter hereof.

Since switches 14 and 16 are both closed while the door is intermediate its path of travel in either direction of movement, the relay structure hereof serves as a safety means, preventing any attempt of the circuit to rotate the motor armature in both directions simultaneously.

Having thus described my invention, what I claim as new and desire to secure by Letters Patent is:

1. An electric control comprising a reversible electric motor; an electric circuit for said motor; a pair of normally open make and break mechanisms in said circuit, adapted when alternately closed to couple said circuit with said motor in reverse relationship respectively; an electromagnet actuator for each of said mechanisms respectively; a control circuit and a holding circuit for each of said actuators respectively, said control circuits being connected in parallel and having a control switch common thereto; a normally open switch in one of said control circuits; a normally open switch in the other of said control circuits; and a normally closed contactor in series with each of said control circuits respectively, said contactors each being disposed for control by the actuator of the opposite control circuit respectively whereby each control circuit respectively is deenergized as the other control circuit is held closed by its corresponding holding circuit.
2. An electric control comprising a reversible electric motor; an electric circuit for said motor; a pair of normally open make and break mechanisms in said circuit, adapted when alternately closed to couple said circuit with said motor in reverse relationship respectively; an electromagnet actuator for each of said mechanisms respectively; a control circuit and a holding circuit for each of said actuators respectively, said control circuits being connected in parallel and having a control switch common thereto; a normally open switch in one of said control circuits; a normally open switch in the other of said control circuits; a normally closed contactor in series with each of said control circuits respectively, said contactors each being disposed for control by the actuator of the opposite control circuit respectively whereby each control circuit respectively is deenergized as the other control circuit is held closed by its corresponding holding circuit.
3. An electric control comprising a reversible electric motor; an electric circuit for said motor; a pair of normally open make and break mechanisms in said circuit, adapted when alternately closed to couple said circuit with said motor in reverse relationship respectively; an electromagnet actuator for each of said mechanisms respectively; a control circuit and a holding circuit for each of said actuators respectively, said control circuits being connected in parallel and having a control switch common thereto; a normally open switch in one of said control circuits; a normally open switch in the other of said control circuits; a normally closed contactor in series with each of said control circuits respectively, said contactors each being disposed for control by the actuator of the opposite control circuit respectively whereby each control circuit respectively is deenergized as the other control circuit is held closed by its corresponding holding circuit; and thermo control means for deenergizing said motor circuit after either control circuit has been held closed for a predetermined period of time.
